UNITED STATES PATENT OFFICE.

ROBERT L. ELLERY, OF TOLEDO, OHIO.

WINDOW RAISING AND LOWERING MEANS.

Application filed September 1, 1922. Serial No. 585,621.

To all whom it may concern:

Be it known that I, ROBERT L. ELLERY, a citizen of the United States, and a resident of Toledo, in the county of Lucas and State 5 of Ohio, have made an Invention Appertaining to a Window Raising and Lowering Means; and I do hereby declare the following to be a full, clear, and exact description of the invention, such as will enable others 10 skilled in the art to which it appertains to make and use the same, reference being had to the accompanying drawings, and to the characters of reference marked thereon, which form a part of this specification.

15 This invention relates to window raising devices for use particularly in connection with closed vehicles, and has for its object the provision of a simple and inexpensive device of this character, which is capable of being easily and quickly installed and is rapid and easy in its manipulation. Further objects and advantages of the invention will be apparent from the following detailed description thereof.

25 While the invention in its broader aspect is capable of embodiment in numerous forms, a preferred embodiment thereof is illustrated in the accompanying drawings, in which,—

30 Figure 1 is an inner side view of a window-casing embodying the invention with parts broken away and with the window in lowered position. Fig. 2 is an enlarged fragmentary section on the line 2—2

35 in Fig. 1. Fig. 3 is an enlarged side elevation of the mechanism embodying the invention removed from a casing with the window raising parts thereof in lowered position and with parts broken away. Fig.

40 Fig. 4 is a section on the line 4—4 in Fig. 3. Fig. 5 is an outer side view of the device in lowered position and with a window glass in engagement therewith and fragmentarily shown. Fig. 6 is an elevation of

45 the opposite side of the device with parts broken away and with the window in partially raised position, and Fig. 7 is a section on the line 7—7 in Fig. 4.

50 Referring to the drawings, 1 designates a window casing which may comprise a door, and is provided with the window opening 2 in its upper portion that is closed by a glass or window 3. This glass when lowered enters a chamber 4 formed within 55 the lower portion of the casing below the

window opening, as is well understood in the art.

The means embodying the invention for controlling the raising and lowering movements of the window 3 includes a plate 5 which is vertically disposed within the casing chamber 4 at the inner side thereof and is fixedly attached at its upper and lower ends to cross-members or bars 6 forming a part of the window casing and which may 60 comprise the customary lining strips of the casing over which the usual upholstering is secured.

A lazy tongs means 7 is carried by the plate 5 at the side thereof adjacent to the chamber 4 for vertical opening and closing movements, and is intended to support at its upper end the window 3 for movements therewith, as hereinafter described. The lower pair of pivotally connected crossed 70 links 8 of the lazy tongs means are pivotally connected at their lower ends to the lower ends of respective suspending links 9, which in turn are mounted at their upper ends on pivot studs 10 fixedly projecting from the 75 lower end portion of the plate 5 near opposite edges thereof.

The center connecting pivot pin 11 of the two lower links 8 of the lazy tongs means is projected at its inner end through a vertical 80 slot 12 in the lower end portion of the plate 5 and is fixedly connected at the opposite side of the plate 5 to the lower end of an operating stem 13, which extends up at the respective side of the plate and at its upper 85 end enters a gear housing 14. One of the pair of spiral gears 15 is threaded on the stem 13 within the housing 14 and the other is fixedly mounted on a shaft 16, which is journaled in the housing 14 and has one end 90 projecting from the housing and carrying an operating crank 17 at the side of the window casing from which it is desired to operate the window raising and lowering means.

The gear 15, which is mounted on the stem 13, is held against axial movements by a pair of fingers 18, which project from a side of the housing 14 at opposite sides of the gear, as shown in Fig. 7.

It is evident that a turning of the crank 17 will drive the 100 gears 15 and communicate an axial movement in one direction or the other to the stem 13 due to the threading of one of the gears thereon, and the movement of the stem will 105 impart a raising or lowering movement of 110

the lazy tongs means through the medium of the pivot pin 11 to which the stem is attached.

The upper ends of the upper pair of crossed pivotally connected links 19 of the lazy tongs means have their upper ends each provided with an extension 20, which projects outward from the upper end of the link at an oblique angle thereto and may 10 itself be straight, curved or angled as desired. A clamp bar 21, which is adapted to have clamping engagement at its upper edge with the lower edge of the window glass 3, is provided with a longitudinally extending slot 22 in the lower edge portion thereof adjacent to each end and each of these slots receives a pin 23, which projects laterally from the free end of each extension 20 whereby the clamping plate 21 and window 20 3 are carried by the upper end portion of the lazy tongs means for raising and lowering movements therewith. During the collapsing and expanding movements of the lazy tongs means the pins 23 work inward 25 and outward in the slots 22 of the clamping plate. The purpose of providing the upper set of links 19 of the lazy tongs means with the extensions 20 angled with respect to the major portions of the links, as shown, is to 30 adapt the clamping plate 21 connecting the upper end of the links 19 to be disposed a distance below the upper end of the lazy tongs means when in closed position and preferably above the upper ends of the major or body portions of the upper set of links 35 19 when in raised position. It is evident that this causes a greater length of movement of the window for each raising and lowering stroke of the lazy tongs means than 40 would be possible if the clamping plate 21 were connected to the lazy tongs means in the usual manner so that when lowered or raised the plate would not be disposed below or above the upper end of the lazy tongs 45 means. The primary object, however, of the extensions 20 angled relative to their respective links 19, is to permit the window to have a maximum lowering movement in the casing chamber 4, irrespective of the height 50 of extension of the lazy tongs means therein when in its collapsed or lowered position.

The purpose of mounting the lazy tongs means on the suspended swinging links 9 is both to impart an accelerated opening or 55 closing movement of the means from a movement of the pin 11 and to impart a greater length of movement to the lazy tongs means from a given movement of the pin 11 than would be possible if the pivots at the lower 60 ends of the lower pair of links 8 were mounted in cross slots in the plate 5, as is customarily done. For instance, a two inch raising movement of the pivot pin 11 from full lowered position will impart a seventeen 65 inch raising movement to the window,

whereas such movement of the pivot pin would impart only a thirteen inch raising movement to the window if the lower pivot pins of the links 8 were mounted in cross slots instead of in the swinging links 9. 70 The provision of the extension arms 20 adds three inches to the above movement.

The weight of the window on the lazy tongs means is counteracted by two coiled contractile springs 25 disposed at opposite 75 sides of the stem 13 and anchored at their upper ends to respective ears 26 projecting from the plate 5. The lower ends of the springs are connected to respective ends of an equalizing cross bar 27 which is centrally pivoted to the pivot pin 11.

I wish it understood that my invention is not limited to any specific construction, arrangement or form of the parts, as it is capable of embodiment in numerous forms 85 without departing from the spirit of the claims.

Having thus described my invention, what I claim as new, and desire to secure by Letters Patent, is,—

1. In combination with a stationary member having a vertical slot, a pair of depending links disposed on opposite sides of the slot and pivoted at their upper ends to said member, lazy-tongs having the lower ends of their lowermost links pivoted to the lower ends of the depending links and having the pivot pin of said lowermost links slidable in said slot, the upper ends of the uppermost links of the lazy-tongs having lateral extensions projecting outwardly in opposite directions, a movable member having horizontal slots, pins carried by the outer ends of said lateral extensions and movably received in the respective horizontal slots of the movable member, a cross-bar centrally pivoted to said lower pivot pin of the lazy tongs, springs connected at their upper ends to the stationary member and at their lower ends to the cross bar, and means connected 105 to said lower pivot pin of the lazy tongs to operate the latter.

2. In combination with a stationary member, a lazy-tongs, means pivoted at their lower ends to the stationary member and depending therefrom and pivoted at their lower ends to the lower ends of the lower links of the lazy-tongs so as to support the latter, means to vertically guide the pivotal pin of the said lower links of the lazy-tongs, means connected to said pin to operate the lazy-tongs, means connected to said pin to tension the lazy-tongs, the upper ends of the upper links of the lazy-tongs having lateral opposed extensions, a movable member, and means to connect the outer ends of said extensions to the movable member.

3. In combination with a support and a movable member, lazy-tongs, links pivoted at their upper ends to the support and de-

pending from the latter and pivoted at their lower ends to the lower ends of the lower links of the lazy-tongs, whereby said lazy-tongs are pivotally supported at their lower ends, the outer ends of the upper links having lateral opposed extensions connected to the movable member, and means to actuate the lazy-tongs whereby upon downward movement thereof the suspension links will

swing outwardly in divergent relation and 10 the lateral extensions will extend downwardly to lie opposite and substantially parallel to and on the outer sides of the suspension links.

In testimony whereof I have hereunto 15 signed my name to this specification.

ROBERT L. ELLERY.
